UNITED STATES PATENT OFFICE.

DENNIS HARRINGTON, OF NEW YORK, N. Y.

MOVABLE CATTLE-PEN.

SPECIFICATION forming part of Letters Patent No. 223,729, dated January 20, 1880.

Application filed September 19, 1879.

To all whom it may concern:

Be it known that I, DENNIS HARRINGTON, of the city, county, and State of New York, have invented a new and Improved Movable 5 Cattle-Pen, of which the following is a specification.

The object of my invention is to provide a device for transporting or moving live stock on foot through the streets of a city.

10 In the accompanying drawings, Figure 1 is a plan of my improvement. Fig. 2 is a side elevation of the same, and Fig. 3 is an end elevation.

Similar letters of reference indicate corresponding parts.

Referring to the drawings, the pen is designated by the letter A. B B are the sides of the pen, sufficiently high to prevent the escape of the stock. These sides are joined at both 20 ends by cross-beams C C', let into the sides B B at top and bottom. There is sufficient vertical space between beams C C' to permit the stock to be driven between them into the pen A without difficulty.

25 To the projecting parts a a of sides B are hinged the doors D D at both ends of the pen. Said doors open outwardly, and when shut they bear against the beams C C', and their outsides are flush with the parts a, as shown 30 in Fig. 1. On one side, to part a, is attached a staple, b, and on the opposite side is a hook, c.

Bars E are used to fasten the doors D D, one end, d, being inserted in the staple b, 35 while the other end, d', is placed in loop e when the doors are closed, thus securely fastening the said doors in the manner clearly shown in the drawings.

A metal bar, F, is placed across the top of 40 the pen, midway of the length thereof, so as to rest on the sides B B. The ends d' d'' of bar F are bent down at right angles and fastened to sides B B.

To the ends d' d'' are fixed axles e e, carrying 45 wheels G G.

The pen is sustained on the wheels G sufficiently far from the ground to permit the animals to move their limbs in walking with perfect ease as the pen is drawn along the 50 street.

In bars E are mortises e e, for the reception of the ends f f of the tongue-hounds g g, to which the tongue H is attached. The ends f f are passed into mortises e e, and secured therein by pins h h, passed down through holes 55 in the bars, (indicated by the dotted lines i in Fig. 3.)

The bars E at both ends of the pen are arranged to receive the tongue-hounds, so that the tongue can be transferred from one to the other, as it is intended that the pen shall be drawn from both ends.

The mode of using the movable pen is as follows: When the animals are to be moved or transported from the ordinary cattle sheds 65 or pens, one end of pen A—say end G'—is drawn up to the open gate of the cattle shed or pen, the doors D D at end G' are opened, and the animals are driven through the open doors D into pen A. When the requisite number 70 have been gotten into pen A doors D D are closed and fastened by bar E. The horses, having been hitched to the opposite end, H', of pen A, are started, drawing pen A with them, and the animals in the pen A are compelled to 75 walk along with the pen A. When the boat, slaughter-house, yard, or other inclosure is reached, the horses drawing pen A are driven through the gateway of said inclosure, so that the end H' of pen A will be close to said entrance. The horses and tongue H are then 80 detached and carried to one side, the doors D at end H' are then opened, and the cattle in pen A are driven therefrom into the inclosure. The horses are then driven into the pen A 85 through open doors D at end H', which are closed after them, thence through doors D at end G', said doors being opened to allow them to pass through, and then closed. The horses are then hitched to end G' of the pen, the 90 gate of the inclosure closed, and the pen A driven off for another installment of the stock.

By this arrangement stock can be moved through the streets of a city with perfect safety to the inhabitants, as it is impossible for the 95 animals to escape from the moving pen. At the same time the arrangement is economical to the stock-driver.

After the tongue H has been attached to the fastening-bar E, the latter may be at any 100

time removed and the doors opened, or the bar may be replaced and the doors locked, without separating the tongue H from its bar E.

5 In the practical use of my improvement this combined use of the bars E and tongue will be found highly convenient.

Having thus described my invention, I claim as new and desire to secure by Letters Patent—

In a cattle-pen, the metallic bar F, placed midway across the top of sides B, and having the bent ends d' d'', in combination with the fixed axles e e, carrying wheels, as shown and described.

DENNIS HARRINGTON.
